UNITED STATES PATENT OFFICE.

WILLIAM N. FAWCETT, OF NEW YORK, N. Y., ASSIGNOR OF ONE-HALF TO MARCUS BRUCKHEIMER, OF NEW YORK, N. Y.

BURGLAR-ALARM.

No. 920,123.

Specification of Letters Patent.

Patented May 4, 1909.

Application filed July 31, 1908. Serial No. 446,313.

To all whom it may concern:

Be it known that I, WILLIAM N. FAWCETT, a citizen of the United States, residing at the city of New York, borough of Brooklyn, county of Kings, State of New York, have invented certain new and useful Improvements in Burglar-Alarms, of which the following is a specification.

This invention relates to improvements in burglar alarms and particularly to that class of burglar alarms known as closed circuit burglar alarms.

The object of this invention is to provide a new and improved attachment which instantly breaks the circuit whenever wires drawn across skylight openings, or ceilings or walls, are cut, after having been short circuited, or are stretched or strained or pulled aside to permit passage of a person, which attachment is simple in construction, can easily be applied, and is very effective and reliable in action.

In the accompanying drawings, in which like characters of reference indicate like parts in all the figures:—Figure 1 is a plan view of my improved automatic switch. Fig. 2 is a side view of the same. Fig. 3 is a diagram showing parts of a single wire circuit combined with my switch.

The switch is mounted on a base 1 of insulating material of suitable size. The switch lever 2 is provided with a longitudinal slot 3 through which a headed stud 4 passes into a boss 5 on the base 1 so that the switch lever 35 can swing on this pivot and can slide in the direction of its length. One end 6 of the switch lever extends into a longitudinal groove 7 formed in the side of an upright plate 8 on the base 1 said plate 8 being 40 slightly shorter than the arc that can be described by said contact end of the switch lever in its swinging movements. A bail shaped check piece 9 extends over the contact end of the switch lever 2 which can 45 strike against the upright ends of the check piece 9. A spring 10 has one end secured at 11 on the base and its opposite end is attached to that end of the switch lever opposite the contact end 6. A wire 12 forming 50 part of the closed burglar alarm circuit is also attached to that end of the switch lever to which the spring 10 is attached. A wire 13 also forming part of the burglar alarm circuit is connected with the plate 8. The wire 55 12 is secured to an insulated binding post at

14 and then passed to and fro across an opening 15, such as a sky light opening or over a wall or ceiling and at its change of direction is passed loosely over or around insulated pulleys or rods 16 and the end of the 60 wire 12 is attached to the switch lever 2 as stated.

The wire 12 is so proportioned in length, that when it is drawn taut it holds the switch lever 2 in central position on the plate 8 and 65 the spring 10 is brought into greater tension. The wire 12 is so spaced in its convolutions over the opening 15 that a man cannot enter unless this wire is cut or forced to one side. The burglar encountering this wire would 70 not cut it unless he had first short circuited it by uniting the points, say *a* and *b* by a wire. If he then cuts the wire 12 between the points *a* and *b* the tension holding the spring 10 is at once released and this spring 75 in contracting throws the switch lever 2 against the end of the stop bridge or check piece whereby the contact between the switch lever 2 and the plate 8 is broken as the end of the switch lever passes beyond the 80 end of the plate 8 making a clean break. This break in the usual manner operates the signal, thus giving notice that the wire has been cut or tampered with. The switch lever while swinging is also moved lengthwise as far as the slot 3 allows, and is moved to such an extent across the end of the plate 8 as to be locked as shown in dotted lines in Fig. 1 and cannot be replaced by pulling on the wire 12 in an attempt to reset the switch. 85 If on the other hand the wire 12 is not cut by the burglar but is forced to one side the additional strain on this wire expands the spring 10 to a greater extent and swings the contact end 6 of the switch lever laterally 90 Fig. 1, until it arrives at the other end of the plate 8 Fig. 1, and snaps over the same thus breaking the circuit and at the same time locking the switch lever. This break thus made also gives a signal showing that some 95 one has tampered with the wires of the burglar alarm system.

I have illustrated and described my device as applied on a closed circuit local battery system. It can of course be used 100 equally as well on any closed circuit system, for example, such as derive the circuit from an outside source, as in all cases my switch breaks the circuit mechanically whenever the taut holding wire is cut or strained suffi- 110

ciently to form an opening or passageway of greater width than that formed between the convolutions of the wire as originally adjusted for use.

5. What I claim as new and desire to secure by Letters Patent is:—

1. In a burglar alarm, the combination with a base, of a switch member pivoted on the base to swing in the arc of a circle, a contact piece against which one end of the switch lever rests and a spring connected with the opposite end of the switch lever, and the conductor wire connected with the switch lever to hold the same in position and 10 in opposition to the spring, substantially as set forth.

2. In a burglar alarm, the combination with a base, of a switch lever having a longitudinal slot, a pivot passing through said 20 slot into the base so as to permit the switch lever to swing and to move in the direction toward the fixed member with which one end of the movable member is normally in contact and a spring connected with said 25 movable member to hold said end against the fixed member, and the conductor wire connected with the switch lever to hold the same in position and in opposition to the spring, substantially as set forth.

30. 3. In a burglar alarm, the combination with a base, of a switch lever having a longitudinal slot, a pivot passing through said slot into the base so as to permit the switch lever to swing and to move in the direction 35 toward the fixed member, with which one end of the movable member is normally in contact and a spring connected with said movable member to hold said end in contact, said fixed switch member having a groove 40 in its side into which groove the free end of the movable member extends and the conductor wire connected with the switch lever to hold the same in position and in opposition to the spring, substantially as set forth.

45. 4. In a burglar alarm, the combination with a base plate, of a movable switch member provided with a longitudinal slot, a pivot passing through the slot into the base member, whereby said movable switch member 50 can swing on its pivot and move in the direction of its length, a fixed member with which one end of the switch member is in contact, said fixed switch member having less length

than the arc described by the end of the movable member and the conductor wire 55 connected with the switch lever to hold the same in position and in opposition to the spring, substantially as set forth.

5. In a burglar alarm, the combination with a base plate, of a movable switch member 60 provided with a longitudinal slot, a pivot passing through the slot into the base member, whereby said movable switch member can swing on its pivot and move in the direction of its length, a fixed member with which 65 one end of the switch member is in contact, said contact member being on the chord of an arc of the circle described by the contact end of the movable member, and being of less length than such chord and the conductor 70 wire connected with the switch lever to hold the same in position and in opposition to the spring, substantially as set forth.

6. In a burglar alarm, the combination with a base plate, of a switch lever mounted 75 thereon to swing in the arc of a circle and to move in the direction of its length, a contact piece against which one end of the switch lever rests, a spring connected with the switch lever to press its end toward the direction of the contact piece, and a stop for the switch lever and located beyond each 80 end of the contact piece and the conductor wire connected with the switch lever to hold the same in position and opposition to the spring, substantially as set forth.

7. In a burglar alarm, the combination with an electrical circuit, of a switch, both members of which form part of said circuit, a spring acting on the movable member of 90 the switch, a restraining means in the shape of an electrical conductor, for preventing the spring from moving the movable member of the switch, said restraining means also forming part of the circuit and guides around 95 which said restraining means is passed loosely, substantially as set forth.

In testimony whereof, I have signed my name to this specification in the presence of two subscribing witnesses, this 27th day of July, 1908.

WILLIAM N. FAWCETT.
